Primary Examiner — Cynthia M. Chin(74) *Attorney, Agent, or Firm* — BCF LLP(57) **CLAIM**

The ornamental design for a kart body, as shown and described.

DESCRIPTION

FIG. 1 is a perspective view taken from a front, left side of a kart body according to my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Throughout the Figures, where shown, the dashed lines are included for the purpose of illustrating portions of the kart body and of a corresponding kart which form no part of the claimed design.

1 Claim, 7 Drawing Sheets(56)
